CLAIM

The ornamental design for a scarf ring, as shown and described.

DESCRIPTION**1.1** : Front**1.2** : Left**1.3**: Top**1.4**: Top

1. Right view is omitted because it is identical with the left view; the broken lines showing a chain represent environment and form no part of the claimed design; the design consists of a scarf ring designed to tie and hold a scarf in place; top view no. **1.3** shows the scarf ring with the chain in the tight position; top view no. **1.4** shows the scarf ring with the chain in the loose position.
